UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,900, dated April 18, 1882.

Application filed March 16, 1882. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification.

The types composing this font consists of an alphabet of Gothic or sans-seriph capitals

with figures and points, as shown in the accompanying impression taken from the types themselves and showing their exact form and outline.

I claim—

The design for types, as described and shown. JOHN K. ROGERS.

Witnesses:

E. PAYSON FISHER,
D. J. HEDDERMON.
